UNITED STATES PATENT OFFICE.

GEORGE R. HOLLAND, OF BROOKLYN, NEW YORK.

HOSIERY BOX.

Application filed October 6, 1920. Serial No. 415,068.

To all whom it may concern:

Be it known that I, GEORGE R. HOLLAND, a citizen of the United States, and a resident of the borough of Brooklyn, city of New York, county of Kings, and State of New York, have invented an Improvement in Hosiery Boxes, of which the following is a specification.

This invention relates to boxes or containers for hosiery, and more particularly to means whereby hosiery is held in such boxes in a predetermined position.

One of the objects thereof is to provide simple and practical means for holding hosiery, and more particularly half-hose, in proper position in the box or container in which it is packed. Another object is to provide means of the above type which although of simple and inexpensive construction, will dependably interlock at its edges with the hosiery. Other objects will be in part obvious and in part pointed out herein-after.

The invention accordingly consists in the features of construction, combinations of elements and arrangement of parts which will be exemplified in the structure hereinafter described and the scope of the application of which will be indicated in the following claims.

In the accompanying drawing, in which is shown one of various possible embodiments of this invention,

Figure 1 is a plan view of a box showing the hosiery in position therein;

Figure 2 is a similar view of the box ready to receive the hosiery;

Figure 3 is a sectional elevation along the line 3—3 of Figure 2;

Figure 4 is a cross-section taken along the line 4—4 of Figure 2; and

Figure 5 is a similar view taken along the line 5—5 of Figure 2.

Similar reference characters refer to similar parts throughout the several views of the drawing.

Referring now to Figure 2 of the drawing, there is shown at 10 an ordinary box of card-board or the like, having side walls 11 and end walls 12. This box is provided adjacent one end with a pair of flaps 13 angularly disposed with respect one to another and cut free from the substance of the box, at the sides and one end of the flap. The flap is bent upwardly using its uncut edge as a hinge, into the upright position shown

in the drawing. These flaps 13 are substantially identical and are so related as to fit within the folded ends of the superposed hosiery 14 as indicated at 15 in Figure 1 of the drawing. The edges of these flaps are preferably serrated as shown at 16 to permit them to bite into the hosiery and more securely hold it against relative slipping.

Adjacent the opposite end of the box are two flaps 17 similar to the flaps 13 and similarly cut from the bottom of the box on three sides and bent upwardly therefrom, using the uncut side as a hinge. Also, the edges of these flaps are serrated as shown at 18. The flaps 17 are inclined with respect one to another as shown in the drawing, instead of extending parallel or lengthwise of the box and thus tend more securely to bite into the upper portion of the hosiery and prevent its slipping away from the adjacent end of the box.

The bottom of the box, and if preferred other portions thereof, are covered with paper as indicated at 19 and as the flaps 13 and 17 are cut from the bottom of the box before this paper 19 is placed in position, the latter is uncut and extends over the openings left by the several flaps. In this manner the box is complete and the hosiery is protected even at these openings.

In the manufacture of the box, the flaps 13 and 17 may be cut from the bottom by a suitable die and may be bent readily upward into the position shown to receive the hosiery. The latter is placed in position and being gripped by and interlocked with the several flaps, is snugly held in the desired form. The entire device is simple and is free from the necessity for added parts as in the case in which separable forms are inserted in a box. Furthermore it is readily manufactured and is well adapted to meet the conditions of hard practical use.

As various possible embodiments might be made of the above invention and as various changes might be made in the embodiment above set forth, it is to be understood that all matter herein set forth or shown in the accompanying drawing is to be interpreted as illustrative and not in a limiting sense.

I claim as my invention:-

1. In a device of the character described, in combination, a box for enclosing hosiery having cut out and bent up from its bottom member two pairs of flaps, one pair of which is adapted to embrace therebetween an

upper portion of hosiery positioned in the box and the other pair of which are positioned at an angle one with another and adapted to engage and support the lower ends of said hosiery, the said box comprising a paper member upon its bottom covering the openings left by said flaps.

2. A device of the character described, comprising a box having formed in its bottom adjacent one end a pair of integral flaps adapted to engage the sides of hosiery positioned therebetween and having adjacent the opposite end a pair of relatively inclined flaps adapted to engage the end of said hosiery and tend to prevent its lateral displacement.

3. A device of the character described

comprising a box having two pairs of flaps cut from the bottom thereof and bent upwardly, the flaps of one of said pairs being positioned to embrace therebetween pairs of hosiery positioned therein, and the flaps of the other pair being positioned to engage and support the opposite end of said hosiery, and a continuous member secured to the lower surface of the bottom of said box and covering the openings corresponding to said flaps, the edges of said flaps being serrated to interlock with the edges of said hosiery.

In testimony whereof, I have signed my name to this specification this 4th day of October, 1920.

GEORGE R. HOLLAND.
